RESONATING CHAMBER CONSTRUCTION
FOR PIANOS

Herbert O. Crippen, Sr., Chicago, Ill.

Application June 4, 1947, Serial No. 752,489

4 Claims. (Cl. 84—189)

1

This invention relates to an improvement in pianos, and more particularly to an improvement whereby the tonal qualities or characteristics of pianos, either of the grand or upright types, may be significantly improved. This improvement is obtained by equipping the pianos with an effective resonating chamber. This application is a continuation in part of my co-pending application, Serial No. 526,262, filed March 13, 1944 now forfeited.

In conventional constructions of pianos, which have long been more or less the same by all manufacturers, a sounding board is suitably supported around its edges by mounting on the side frame or rim of the piano case, the strings of the instrument being stretched between points on a metal frame and a pin block as usual and disposed adjacent one face of the sounding board, the other face of the sounding board being provided with reinforcing ribs and left exposed to the atmosphere. In other words, the bottom of a grand piano and the back of an upright or spinet type piano have been left open to expose the bottom or back of the sounding board visibly to the atmosphere outside of the piano case.

I have previously proposed the application of a resonating chamber to a piano sounding board by attachment of a specially constructed chamber to the central portion or back of the sounding board accompanied by the removal of the reinforcing rib portions in the area covered by the special resonating chamber. This is shown in my Patent 1,530,984 issued March 24, 1925. That construction has been considered impractical for various reasons such as the required changing of the accepted piano structure including the removal of the sound board reinforcing ribs or portions thereof and the resulting loss of sounding board reinforcement and impairment of its musical functions, interference with proper vibration of the sounding board by the attachment of the resonating chamber to the bottom or back of the sounding board, the high cost of constructing the special chamber, the great difficulty of securing effective attachment thereof to the sounding board without the tabooed use of nails or screws entering the sounding board, the impracticality of placing the tone post between the sounding board and the back of the chamber under adequate compression between said sounding board and back because of the inherent weakness of attachment of the resonating chamber to the sounding board, and perhaps other reasons.

The main object of the present invention is to provide an effective resonating chamber in a

2

piano without requiring significant changes in the construction of the sounding board, its reinforcement, the piano frame or case or any other part of the conventional piano structure. Another object is to provide a piano resonating chamber which can be produced and applied at a very low cost so as to avoid unduly increasing the cost of constructing a piano embodying the improved resonating chamber. Still another object is, as already indicated, to provide a piano resonating chamber which will accomplish its resonating function without incidentally impairing the normal functioning of the sounding board, and, in general, it is the object of the invention to provide a piano embodying improved tonal qualities or characteristics without materially complicating or increasing the cost of constructing the instrument.

Other objects and advantages of the invention will be understood by reference to the following specification and accompanying drawings wherein the application of a resonating chamber according to the present invention is illustrated in respect of both a grand and an upright piano.

25 In the drawings:

Fig. 1 is a top plan of a grand piano, the cover being omitted;

Fig. 2 is a bottom plan of the grand piano, a part being shown broken away to more clearly illustrate certain details;

Fig. 3 is a fragmentary perspective illustrating the principal details of construction with which this application is concerned; and

30 Figs. 4 and 5 are back and transverse sectional views respectively of an upright piano to which the invention is applied.

In a so-called grand piano, that is a piano in which the sounding board and strings are disposed in a substantially horizontal plane, the present improvement is embodied by mounting a rather stiff or rigid wood panel 1 in the piano case or frame so as to close the bottom area thereof, and by interconnecting such panel and the sounding board 2 of the piano by means of one or more tone posts such as shown at 3. Also, the sounding board is equipped with one or more sound openings or holes 4.

The piano case consists of a frame or rim member 5 which extends around the back and across the sides of the piano, usually terminating at a junction with the key section. Within the member 5 there is a reinforcing rim or element 6, usually somewhat thicker than the wood of which the member 5 is formed. The sounding board 2 is mounted around its rear and side portions on

the upper edge 7 of said reinforcing member 6, the sounding board usually being securely glued to said edge 7.

The strings indicated at 8 are stretched in the customary manner between pins carried by a pin block (not shown) and pins carried by a metal frame or string plate 9 which is disposed above the sounding board 2 in spaced relation thereto except to the extent that the plate 9 may have boss-like marginal portions seated directly on the sounding board or on a suitable mounting strip or block in accordance with conventional practice. The string plate is, of course, suitably secured to the underlying portions of the case reinforcement 6. The usual curving bridge 10 is interposed between the strings and the sounding board in the usual manner.

The front edge of the sounding board, that is the edge thereof which extends substantially parallel to the length of the keyboard of the instrument, is supported on the upper edge of a transverse frame member 11 which extends between and joins the opposite end portions of the outer case 5 and its inside reinforcing member 6.

On the bottom side of the sounding board, there are provided a series of diagonally extending stiffening ribs 12, these ribs being applied to the sounding board in a conventional manner and serving their usual purposes of reinforcing the sounding board and transmitting or spreading vibration over the area of the sounding board transversely of the grain direction of the sounding board. The sounding board and reinforcing ribs are of straight grained spruce-pine construction as usual.

The sounding board 2 is set in motion in harmony with the vibration imparted to the strings 8, mainly by motion transmitted from the strings to the sound board through the bridge 10, and the vibratory motion of the sounding board is transmitted through the agency of said one or more tone posts to the back panel of the resonating chamber formed by the panel 1.

The illustrated tone post 3 is shown located at a point of the sounding board substantially in register with a portion of the bridge, approximately under or adjacent to the point at which the middle C strings cross over the bridge. A single sound opening may be provided in the sounding board 2 adjacent said tone post 3 and preferably forwardly of the bridge. Additional tone posts and openings, or either of them, may be provided. For example, as shown in Figs. 1 and 2, a sound opening is provided in association with the opening 4 but beyond or to the rear of the bridge, said openings 4 and 4a constituting one pair of openings with the tone post 3 between them, and similar pairs 4b and 4c of openings are provided at suitable points above and below the middle C location of the tone post 3 and opening pairs 4 and 4a. In this instance, there is no tone post (other than the middle C tone post) associated with the opening pairs 4b and 4c.

Larger pianos may advantageously be provided with two or more sound openings or two or more pairs thereof, whereas smaller pianos may be adequately served by a single opening. Also, the size and shape of the opening as well as the number and location thereof may be varied to procure the desired tonal effects.

Sounding boards are usually crowned or arched somewhat, often so that a central point is approximately $\frac{1}{2}$ inch higher than its periphery. The reinforcing ribs 12, of course, are made to conform to such arching, the sounding board

being usually of substantially uniform thickness so that on the bottom side, the sounding board is concave in parallelism to the convex arching of the top or string side. This arched construction serves to aid the sounding board to withstand the pressure exerted thereon by the strings which are under very high tension so that they exert considerable down pressure (often of the order of 600 pounds) on the bridge and on the sounding board. This down pressure is a steady load subject to relatively small changes resulting from the vibration of the strings. Hence, it can be seen that the sounding board must be a very strong unit, and for lasting results, must be adequately braced by ribs such as the ribs 12 to prevent its being collapsed by the said down pressure of the strings.

The tone post 3 is preferably fixedly positioned by having its lower end recessed into the closure panel as shown at 13, the fit being a drive fit so that there can be no significant relative movement between the tone post and the closure panel 1. The sounding board end of the tone post is caused to tightly abut the bottom of the sounding board, but it is preferably not recessed into the latter because of the difficulty of properly aligning recesses therein with the closure panel recesses to receive the opposite ends of the tone posts, and because of other reasons, including the weakening effect of recesses if cut into the sounding board.

The tone post is preferably made of the same material as the sounding board and its reinforcing ribs, and it is selected of such length that when the instrument is assembled, the tone post will be under sufficient compression between the sounding board and the closure panel to prevent the occurrence of any significant relative movement between the sounding board and the adjacent end of the tone post, or between the closure panel and the adjacent end of the tone post whether or not any adhesive is applied at the ends of the tone post. Normally, the recessed seating of the tone post will be sufficient to position it without any other fastening.

In constructing a piano, the case structure will be produced in the usual manner, but before the sounding board is inserted, the closure panel 1 may be seated on an inwardly projecting ledge provided by an inwardly projecting shoulder strip or closure mounting strip 14 which is preliminarily secured by gluing (with or without additional fastening) to the lower portion of the reinforcing rim element 6. The closure panel will preferably be adhesively secured to said mounting strip 14 adjacent the side portions of the piano, and at its front end, said closure panel will be similarly supported on a mounting strip 15 which is secured to a transverse frame member 16 which is a standard part of a conventional grand piano construction. Said transverse member 16 is secured to a bottom member 17 of the keyboard section of the piano.

Either before or after the closure panel 1 is properly secured in place, the tone post 3 (or all that are used) are seated in the closure panel as already explained. Thereafter, the sounding board is set into the case and secured on the supporting inner frame 6 in the usual manner followed by application of the string plate, strings, etc. The sounding board is securely held down by its own attachment to the frame part 6 and additionally by the attachment of the overlying string plate to said frame part. Hence, the sounding board and closure panel are each secured to said case part 6 so as to be well

adapted to maintain said tone posts under substantial pressure between them.

In addition to providing a resonating chamber, the described structure provides supplemental support for the arched sounding board so that the down pressure of the strings will be more strongly resisted and the effective life of the sounding board arch prolonged. It may be observed in this connection that the arched sounding board of conventional pianos tends to become flattened under the down pressure of the strings, and that it is a common practice for piano manufacturers to include in the reconditioning of an old piano, the re-arching of the sounding board. This arching is important both because of its effect in enabling the sounding board to withstand the down pressure of the strings, and also because of its effect in enabling the sound board to more adequately reproduce the vibratory motions imposed on it when the strings are struck by the hammers of the piano. One such hammer is represented in the drawings at 18.

The closure panel 1 may be made of any suitable wood or other material. In view of present piano practices, it is preferable that the closure panel 1 be constructed of clear hard maple, and preferably in the form of strips joined edge to edge by gluing substantially in accordance with the construction of a conventional sounding board; the strips may have tongue and groove connections if desired.

Grand pianos are usually made with one or more transverse braces such as represented by dotted lines 19. Such braces are spaced downwardly from the sounding board so as to avoid any interference with the proper functioning thereof. These transverse reinforcing braces may be entirely dispensed with since their function will be substantially performed by the closure panel which is secured to the side frame or rim of the piano case. The saving in cost incident to the said elimination of these usually heavy braces, and the labor of applying them, will largely, if not wholly, cover the cost of providing and installing the described resonator elements.

In general, the only change involved in embodying the described resonating chamber is to eliminate the heavy frame braces underlying the sounding board, provide a supporting ledge such as the ledge 14-15, and to provide and seat the closure panel 1 with its tone post (or posts). This departure from standard piano construction thus involves no radical changes in standard constructions, but mainly the provision of the additional elements indicated. Hence, the production of a piano with the improved resonating chamber involves no extensive new details of construction, and involves no modification of established and accepted principles of piano construction. Also, these additional elements are of simple and relatively inexpensive character which should add but little to the cost of the instrument in view of the saving effected by omitting the heavy frame braces.

A resonating chamber may be provided in an upright type of piano as represented in Figs. 4 and 5, wherein a closure panel 20 is shown recessed into the back of the piano and seated on mounting strips 21 secured to the sides 22-22 of the piano case and on frame members 23-23 which extend across the top and bottom of the case at the back thereof. The rib reinforced sounding board 24 is provided with a plurality of pairs of sound openings in the form of

f-shaped holes such as represented at 25 and a plurality of tone posts such as 26 respectively disposed between the openings of each pair. The tone posts are under compression between the sounding board 24 and back panel 20 substantially as above explained in connection with the tone post 3 and the sounding board 2 and back panel 1.

The conventional, vertically extending, intermediate back frame members or struts such as represented in dotted lines at 27 in Fig. 4, may safely be omitted since the strong back closure panel 20 supplies all the reinforcement that is actually required. However, if preferred, suitable substitute struts may be provided either outside of the closure panel 20 or between the panel 20 and the sounding board 24, depending upon construction details of the piano to which the resonator is being applied. In this instance, a well known make is represented in Figs. 4 and 5 wherein the strings and sounding board are disposed at an angle, and in which the closure panel is set parallel to the sounding board.

Some technicians assert that the point of greatest vibration of the strings and sounding board occurs at a point equal to about $\frac{1}{6}$ of the length of the respective strings forwardly of the bridge. The sound opening or openings and also the tone post or posts may accordingly be located a corresponding distance forwardly of the bridge, i. e. $\frac{1}{6}$ of the length of the overlying strings forwardly of the bridge. Hence, in Figs. 1 and 2 the sound openings which are located forwardly of the bridge are shown at progressively varied distances from the bridge while the openings to the rear of the bridge are located at approximately uniform distances from the bridge. Similarly, in Fig. 4, the pairs of openings and associated tone posts are shown at different distances from the bridge.

Various changes in the details of the described construction and in the positioning of the tone posts and sound openings, as well as in the number of said tone posts and the shape and number of said openings may be made while employing the principles of the invention.

I claim:

1. A piano having a sound board, tensioned strings on the front side of said sound board, a case or frame extending around said sound board and supporting the same, said frame extending laterally from the sound board beyond the back side thereof so as to cooperate with the sound board to form a recessed area, a closure panel for said recessed area secured directly to said case in spaced relation to said sound board, said closure panel cooperating with said case and sound board to form a resonating chamber, said resonating chamber being provided with a sound opening communicating with the interior of said chamber.

2. A piano having a case and sounding board mounted on the case within the same, tensioned strings extending over one face of said sounding board and reinforcing ribs secured to the opposite face of said board, said case extending laterally from said sounding board beyond its rib reinforced face so as to cooperate with said sounding board to provide a recessed area within said case, a closure panel spaced from said sounding board and peripherally mounted on said case independently of said sounding board, and a tone post under compression between said sounding board and closure panel, said sounding board, case, closure panel and said tone post cooperat-

ing to form a resonating chamber, said resonating chamber being provided with a sound opening communicating with the interior of said chamber.

3. In a piano, a sound board bowed to provide a substantially convex surface, a plurality of vibratory strings arranged over said surface, a bridge on said surface over which said strings are tensioned, said sound board having a plurality of spaced pairs of f-shaped holes located inwardly of said bridge in areas coinciding with the regions of the greatest vibration of said strings, a wall substantially co-extensive with said sound board and spaced therefrom, and a tone post located between each pair of f-shaped holes, said tone posts being under compression between and intimately connecting said sound board and said wall.

4. In a piano, a resonant chamber comprising a sound board bowed to provide a substantially convex surface, a wall substantially co-extensive with said sound board and spaced therefrom, a

5
10

frame enclosing said sound board and said wall, a plurality of vibratory strings arranged over said convex surface, a bridge on said surface over which said strings are tensioned, said board having a plurality of spaced pairs of f-shaped holes located inwardly of said bridge in areas coinciding with the regions of greatest vibration of said strings, and a tone post located between each pair of f-shaped holes, said tone posts being under compression between and intimately connecting said sound board and said wall.
